UNITED STATES PATENT OFFICE.

LOUIS R. E. WASKINS, OF EDGEWATER, COLORADO.

AUTOMOBILE-DOOR LOCK.

Application filed March 9, 1922. Serial No. 542,274.

To all whom it may concern:

Be it known that I, LOUIS R. E. WASKINS, a citizen of the United States, residing at Edgewater, county of Jefferson, and State of Colorado, have invented certain new and useful Improvements in Automobile-Door Locks; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to locks and has special reference to a lock adapted to be applied to an automobile door.

It is well known that automobile door locks of the ordinary construction require the door to be closed with considerable force for the reason that the bolt usually projects from the lock and must be moved back against the spring tension and the friction.

It is the object of this invention to produce a lock which shall be so designed that when the bolt is withdrawn on opening the door it will be held in retracted position until the door is again closed. When the door has reached a position in which it is nearly closed, an automatically operated means will release the bolt which will then be projected outwardly by means of a spring. In the manner just described it becomes possible to close the doors gently and still secure successful operation of the lock.

In order to more clearly describe my invention, I shall have reference to the accompanying drawing in which—

Fig. 1 shows an elevation of an automobile car door with parts broken away to show the location of the lock.

Fig. 2 is a section showing the relative location of parts with the bolt in unlocking position.

Fig. 3 is a view similar to Fig. 2 and shows the relative position of the parts with the bolt in locking position.

Fig. 4 is a vertical section taken on line 4—4 Fig. 3.

Fig. 5 is a view similar to Fig. 3 showing a slightly modified form of lock.

Fig. 6 is a section taken on line 6—6 Fig. 5 showing the lock in operative position and

Fig. 7 is a section similar to that shown in Fig. 6 showing the bolt in unlocking position.

The same reference numerals will be used to indicate the same parts throughout the several views.

Numeral 1 represents the side door of an automobile and 2 represents the lock which I will now describe. 3 represents a shallow box-like housing similar to that usually employed in connection with ordinary locks. Slidably connected with the casing is a bolt 4 which is guided in its movements by lugs 5. A spring 6 engages the inner end of the bolt 4 and tends to keep it normally in the projected position shown in Fig. 3.

In order to reciprocate the bolt 4, I provide a bell crank lever 7 which is pivoted to the casing by means of a pivot 8. The vertical arm 9 of the bell crank carries a pin 10 which engages with the transverse slot 11 in bolt 4. When arm 9 is rocked about the pivot 8 by means of a handle which may be attached to the pivot 8 or by other means which will be hereinafter described, the bolt 4 will be reciprocated between the guides 5. Bell crank 7 has a substantially horizontal arm 12 and this is provided with a pin 13, which co-operates with a slot 14 in the lower end of handle 15. When the handle 15 is pulled upwardly against the tension of spring 16, it will rotate the bell crank lever 75 in a clockwise direction and move the bolt 4 inwardly against the tension of spring 6. In order to hold the bolt in retracted position after it has been moved to that position by the handle 15, I provide near the outer end thereof a notch 17 and arranged transversely of bolt 4 is a locking member 18 which has intermediate its ends a notch 19. Member 18 is guided in its travels by lugs 20 which may be cast integral with the housing. A spring 21 exerts a force on the upper end of locking member 18 which tends to make it move downwardly and as a result of this it will drop into notch 17. Whenever the bolt 4 is pulled back sufficiently to bring the notch in line with the locking member, the bolt will be held in retracted position until member 18 is moved upwardly a sufficient distance to disengage it from the notch.

In order to secure the automatic release of bolt 4 when the door is closed, I extend the lower end of locking member 18 out through the lower side of housing 3 and provide it with a roller 22 whose function it is to engage the incline 23 on the door jamb as the door is closed. When the roller 22 strikes the incline 23 it will move the locking member 18

upwardly a sufficient distance to permit the bolt 4 to be released. Spring 6 will then force the outer end of the bolt against the nose plate 24 and cause it to move into the opening 25 when the door is fully closed. From the above description it will appear that my lock is so designed that the bolt will be locked in retracted position when the door is opened and held in this position until 10 the door is closed, when it will be automatically released by means of the incline 23 roller 22 and locking member 18.

In Figs. 5, 6 and 7, I have shown a slightly modified form of lock in which the sliding locking member 18 has been replaced by a locking member 26 which is pivotally connected to the front of the housing by means of a pivot 27. A spring 28 is provided for the purpose of biasing member 26 in a counter-clockwise direction. Bolt 4 is provided on its upper surface with a notch 29 into which locking member 26 drops when the bolt is withdrawn—see Fig. 7. Within the casing I provide an ear 30 within which is slidably 20 mounted a pin 31 which is of such length that when its outer end is substantially flush with the casing the locking lever 26 will be held in the position shown in Fig. 6, and when the lever 26 is in locking position (Fig. 30) the end of pin 31 will extend a short distance outside of the casing. I provide a plate 32 on the door jamb in such a position that the pin 31 will strike against the same as the door is closing and thus release the bolt 4 and permit the spring 6 to project the same into the hole 25 in nose plate 24. My lock may be opened by means of a lever 15 in the manner above described or a handle may be attached to the pivot pin 8. 40 From the above it is apparent that I have provided a lock which is adapted to be used in connection with doors of various descriptions and which will make it possible to close the door gently thus avoiding the excessive wear and tear due to the necessity of slamming the door in the manner now common.

Having now described my invention what I claim as new is:

1. A lock comprising a narrow rectangular housing, a plurality of guides secured to one side thereof, a bolt slidable between said guides, a spring co-operating with said bolt and tending to project the same from the housing into locking position, a bell crank pivoted to the housing and having one end thereof pivotally connected to the bolt, a handle connected to the other end of said bell crank lever by a lost motion connection, said handle projecting out through the housing, a notch in one side of said bolt, a locking member slidable transversely of said bolt and adapted to engage said notch and hold the bolt in retracted position, a spring co-operating with said locking member tending to force it into locking engagement with the bolt, said locking member projecting through the side of the casing, and a rotatable handle attached to the bell crank whereby the latter may be operated independently of the handle. 70

2. A lock comprising a housing, a locking bolt slidably connected therewith, a spring co-operating with said bolt for biasing the latter to locking position, a bell crank lever pivotally mounted in said casing and having one arm thereof pivotally connected with the bolt, means for rotating said bell crank lever on its pivot whereby the bolt is reciprocated in the housing from locking to unlocking position, said means comprising a handle slidable in said housing and connected to the other end of said bell crank lever by lost motion connection, locking means movably secured to said housing, a notch in said bolt adapted to cooperate with the locking means when the bolt is in unlocking position, and means for releasing the said locking means. 80

In testimony whereof I affix my signature.

LOUIS R. E. WASKINS.
